UNITED STATES PATENT OFFICE.

LONZO D. DUTTON, OF WINFIELD, KANSAS, ASSIGNOR OF ONE-HALF TO EDWARD M. MARTIN, OF WINFIELD, KANSAS.

LOCK-CONTROLLED VALVE.

1,289,415.

Specification of Letters Patent. Patented Dec. 31, 1918.

Application filed March 2, 1917. Serial No. 152,115.

To all whom it may concern:

Be it known that I, LONZO D. DUTTON, a citizen of the United States, and a resident of Winfield, in the county of Cowley 5 and State of Kansas, have invented a certain new and useful Improvement in Lock-Controlled Valves, of which the following is a specification.

The present invention relates to valves, 10 and particularly to that type which are adapted to be locked in closed position to prevent the unauthorized flow of a fluid through the valve.

An object of the present invention is to 15 provide a lock-controlled valve of this character which is particularly adapted for motor vehicles and the like and adapted to be interposed between the supply tank and the motor to prevent the unauthorized use of the 20 motor vehicle, and to prevent the withdrawing of the contents of the fuel tank by unauthorized persons.

Another object of the present invention is to provide a relatively simply constructed 25 valve of this nature which may be incorporated in a fuel supply line, and which may be operated or controlled by the use of a relatively small key.

The invention still further aims at the 30 provision of a valve of this character which is so constructed that the adjustable and detachable parts thereof are effectively housed in a strong casing to which access cannot be readily had.

Various other objects and advantages of 35 this invention will be in part described, and in part understood, from the following detailed description of the present preferred embodiment, the same being illustrated in 40 the accompanying drawings wherein:

Figure 1 is a longitudinal section through a lock-controlled valve constructed according to the present invention, the same being illustrated as applied to a fuel-supply and 45 a device adapted to receive the fuel.

Fig. 2 is a top plan view of the same, the upper portion of the valve being shown in section on the line 2—2 of Fig. 1.

Fig. 3 is a fragmentary enlarged trans- 50 verse sectional view taken through Fig. 1 on the line 3—3.

Fig. 4 is a fragmentary section taken on the line 4—4 of Fig. 1.

Fig. 5 is a plan view of a key which may 55 be employed for operating the valve.

Referring to this drawing, wherein like parts are designated by similar characters of reference throughout the several views, A designates a source of fluid supply, such as a pipe, and B designates a device adapted to receive the fuel, such as a carburetor or the like.

The valve of this invention comprises a casing or body 10 which is preferably of spherical form, as disclosed, and which is made of steel or other relatively hard substance. The valve casing 10 is provided with a through port 11 which is co-extensive with the opposite end projections 12 and 13 adapted to be secured in any suitable manner to the parts A and B. The casing 10 is provided upon its upper side with a cylindrical hollow projection 14 having an in-turned flange 15 at its upper end. The opening in the projection 14 is in the form of a counter-bore which is formed from the bottom upwardly through the valve body 10, and is adapted to receive therein a rotatable disk or plate 16, the latter having a marginal shoulder adapted to engage beneath the flange 15 to retain the disk from moving upwardly from the projection 14. A cylinder 17 is fitted in the valve body 10 and extends upwardly into the projection 14 and against the under side of the disk 16 to hold the latter in place. The cylinder 17 is held from rotation by the provision of a locking pin 18 which is introduced laterally through the projection 14 and engages through the adjacent side of the cylinder 17. The disk 16 is provided at its central portion with a diametrically extending key-hole or slot 19, and the cylinder 17 is provided with a plurality of guards 20 which project from the inner wall of the same.

The valve casing or body 10 is provided with a counter-bore at the lower end of the body 10, and which is adapted to receive a bushing or sleeve 21. The bushing or sleeve 21 is provided with a diametrically extending opening through its lower end registering with the through passage 11 of the casing and which is provided with a relatively large axial opening which tapers downwardly toward the open end of the body 10. The lower or outer end of the sleeve 21 is externally reduced to provide an annular projection 22, and a turning plug 23 is fitted in the sleeve 21 and is correspondingly tapered to fit snugly therein. A disk or plate 110

24 is secured by means of a screw 25 to the reduced end of the turning plug 23 and overlaps at its marginal edge the cylindrical projection 22 of the sleeve 21. The open end 5 of the counter-bore in the casing 10 is closed by a screw plug 26 which conforms at its exterior surface to the spherical contour of the casing, and which has a concavity 27 at its inner end to accommodate the plate 24 and the screw 25.

The upper end of the turning plug 23 is provided with a relatively deep diametrically extending slot 28 arranged in axial alignment with the cylinder 17 and the disk 16.

A gasket or washer 29 is fitted in the inner end of the counter-bore of the casing 10 and is held in position by the adjacent end of the sleeve 21, the latter being held rigidly 20 against the washer 29 by the annular upstanding flange 30 of the plug 26.

As shown in Fig. 5, the key 31 employed is of the double-bitted flat type and is provided in its opposite edges with two sets of kerfs 32 and 33 adapted to receive therethrough the guards 20 when the key 31 is turned for registering the lower end of the blade of the key with the slot 28 of the turning plug 23, and for subsequently turning the key after the latter has been placed in the slot 28.

In operation, it is only necessary to insert the key 31 through the slot 19 of the disk 16, and to turn the key with the disk 16 until the lower end of the key blade passes between the transversely registering slots between each adjacent pair of the guards 20. It will be noted particularly from Figs. 2 and 3, that the guards 20 are arranged in 35 the form of quadrants with their adjacent edges closely spaced apart to provide intersecting diametrically extending passages or slots through which the blade may pass. It will also be noted that the guards 20 are arranged in vertical alignment in the present instance, although it is of course understood that various arrangements and numbers of the guards 20 may be resorted to.

When the key blade is inserted, and if it 50 does not register with the slot 28 in the turning plug 23, the upper end of the turning plug will hold the key from being further depressed. In this latter position, the kerfs 32 register with the guards 20 and the key 55 31 with the disk 16 may be turned in either direction to register the lower end of the key blade with the slot 28. When this latter has been done, the key may be depressed into the slot 28, and the kerfs 33 are now brought 60 into register with the guards 20.

If the key 31 should happen to be inserted with its inner end crosswise of the narrow slot 28 in the plug 23, the key would be held 65 from moving down into the plug and would have to be withdrawn from the barrel 17

were it not for the kerfs 32, the latter admitting the turning of the proper key in the barrel to register with the slot 28. The guards 20 are arranged in registering groups of four each equi-distantly spaced in 70 a circular row and provide a pair of intersecting longitudinal key ways in the barrel arranged at right angles to each other.

The key 31 may now be turned with the disk 16 and the turning plug 23 to rotate 75 the latter through a quarter turn and open or close the through passage 11 in the casing 10.

It will thus be seen that a key having a blade of the required thickness must be used, 80 and that the key must have the kerfs 32 and 33 formed correspondingly to the number and the location of the guards 20 in the non-rotatable cylinder 17.

It is of course understood that various 85 changes and modifications may be made in the details of construction of the above specifically described valve and the locking means therefor without departing from the spirit of this invention, and being restricted 90 only by the scope of the following claims.

I claim:

1. In a valve, the combination of an integral casing having the usual fluid passage therethrough and provided with a projection whose axis lies at an angle to the fluid passage, the casing having a bore therein extending into the projection and coaxial therewith reduced at the outer end of the projection for forming a retaining flange 100 thereat and opening through the casing at the side opposite to the projection, a barrel fitting in the bore of the projection against the flange and having a key way therein opening through the projection, a turning 105 plug fitting in the bore and having a transverse perforation adapted to register with the fluid passage and a key slot in its end adjacent the barrel for retaining the end of a key inserted through the barrel, and securing 110 means in the open end of the bore for sustaining the turning plug therein.

2. In a valve, the combination of a casing provided with an integral projection with a bore in said projection and a counter-bore in 115 the casing, a cylinder key-way fitting through the casing in said projection and provided with guards upon its inner wall, a turning plug fitting in the counter-bore to control the passage of fluid through the casing and provided with a key-receiving part adjacent said cylindrical key-way, and means for closing the outer end of the counter-bore to house said turning plug and said cylindrical key-way in the casing.

3. In a valve, the combination of a casing provided with an integral hollow projection and a counter-bore at the inner end of the projection, a cylinder fitting through the casing into the hollow projection and having 130

guards upon its inner wall, a ported bushing fitting in said counter-bore, a turning plug carried by the bushing for controlling the passage of fluid through the casing, said 5 turning plug being provided with a key-receiving part adjacent to said projection, means carried upon the turning plug for engagement with the bushing to hold the turning plug therein, and a closure for the outer 10 end of said counter-bore to house the bushing and the turning plug in the casing.

4. In a valve adapted to be locked, the combination of a casing having a longitudinal fluid passage therein and a projection 15 at one side, and having a transverse bore extending into the projection and intersecting

the passage, a barrel fitting in the projection and having a key way therein, a washer bearing against said barrel, a bushing fitting in the bore and having a tapering opening therethrough, a turning plug fitting in the opening of the bushing and having a key slot in its end adapted to register with the key way in the barrel, means for retaining the plug in the bushing, said plug and bushing having transverse ports therethrough adapted to register with the fluid passage, and securing means in said bore of the casing engaging the bushing to hold it in the bore and in endwise engagement with said 20 25 30 washer.

LONZO D. DUTTON.
